(57) **CLAIM**

The ornamental design for a radiator grill for a automobile, as shown and described.

DESCRIPTION

FIG. 1 is a front perspective view of a radiator grill for automobile showing my new design;

FIG. 2 is a front view thereof;

FIG. 3 is a rear view thereof;

FIG. 4 is a left side view thereof;

FIG. 5 is a right side view thereof;

FIG. 6 is a top view; and,

FIG. 7 is a bottom view.

Inventive aspects of the radiator grill exist in the grill exterior as a whole, in portions and elements thereof, and in combinations of portions or elements thereof. Applicant reserves the right to amend this application and/or to file one or more divisional applications to specifically claim any such arrangements or any specific embodiment or embodiments.

Some of the drawings may include trademarks and other indicia thereon. Applicant's invention also includes the design without the trademarks and other indicia thereon. Applicant's invention further includes a continuous surface and/or pattern in lieu of the trademarks and/or other indicia.
